his Attorney

UNITED STATES PATENT OFFICE.

JAMES A. HOWE, OF ROCHESTER, NEW YORK, ASSIGNOR TO TAYLOR INSTRUMENT COMPANIES, OF ROCHESTER, NEW YORK, A CORPORATION OF NEW YORK.

COMPASS.

1,253,197.

Specification of Letters Patent.

Patented Jan. 8, 1918.

Original application filed March 21, 1914, Serial No. 826,190. Divided and this application filed February 1, 1915. Serial No. 5,391.

To all whom it may concern:

Be it known that I, JAMES A. HOWE, of Rochester, in the county of Monroe and State of New York, have invented certain new and useful Improvements in Compasses; and I do hereby declare the following to be a full, clear, and exact description of the same, reference being had to the accompanying drawings, forming a part of this specification, and to the reference characters marked thereon.

My invention has for its object to improve and simplify the construction of pocket compasses by affording a structure embodying a minimum number of parts which can be manufactured at comparatively low cost, this being a division of an application which resulted in Letters Patent No. 1,136,232, dated April 20, 1915. A further purpose of the invention is to provide a device that can be so economically manufactured as to permit it to be sold at a reasonably low price, and at the same time one that is characterized by high class workmanship and accurate and reliable results. Another object of the invention is to enable the several parts of the device to be manufactured with a minimum number of operations, and to make it possible for said parts to be readily assembled, without requiring great experience or unusual care in the assembling, while affording a finished article that possesses all the qualifications of a high priced instrument, and which will not be seriously affected by rough work or careless usage. To these and other ends the invention consists in certain improvements and combinations of parts all as will be herein-after more fully described, the novel features being pointed out in the claims at the end of the specification.

In the drawings:

Figure 1 is a plan view of a pocket compass constructed in accordance with my present improvements;

Fig. 2 is a vertical sectional view taken centrally of Fig. 1;

Fig. 3 is a sectional view similar to Fig. 2, and showing the needle support elevated off its bearing, and

Fig. 4 is an enlarged sectional view taken centrally through the head of the casing.

Similar reference characters in the several views indicate the same parts.

My invention is not limited in its application to the specific structure shown herein or to compass constructions, since it possesses certain meritorious features which are susceptible of application to other devices, such as watches, as well as articles of a similar nature, and in the present embodiment I have shown an example of a method of carrying out the features of my invention as applied to a compass embodying an outer casing A which may be stamped in the shape shown from an integral sheet of metal. The outer casing A is curved or rounded in substantially the manner shown, and has an opening in one face surrounded by an inwardly directed edge a for a purpose that will appear presently.

Arranged within the outer casing A is an inner casing B which may also be stamped from a single integral sheet of metal and embodies a bottom b and an outwardly directed lip or flange b' at its free edge terminating in a reversely or inwardly bent portion b² which is adapted to engage a crystal C. In assembling the parts, the crystal C is first snapped or forced into the inner casing B, being held upon the lip b' by its engagement with the portion b². The inner casing B is then forced into the opening of the outer casing A until the edge of the latter engages the lower face of the lip or flange b'. The inner casing fits tightly within the outer casing so that it is held effectively against movement, due to frictional engagement and the resiliency of the outer casing. In addition to holding the inner casing in position, the outer casing A also serves an additional function by contracting the upper edge of the inner casing to a greater or less degree, and thereby holding the crystal C more rigidly in position.

The bottom b of the inner casing is provided with a bearing for the needle support, and in the present instance, this is accomplished by providing an opening in the bottom of the casing to receive a bushing D. The bushing is bored centrally to receive a metallic pin or needle d which is driven in, and held preferably by frictional engagement, and I have found that for the purposes of the structure described, the ordinary steel needle, such as employed in sound reproducing machines, can be successfully used for this purpose, and as these can be pur-

chased in large quantities at a very low cost it reduces considerably the expense of the instrument. It is only necessary to drive the needle into the bushing a certain distance, and then cut off the surplus of the base portion of the needle projecting beyond the bushing. In assembling this portion of the device, a suitable dial *E* is first positioned on the inner face of the bottom of the inner casing, the bottom end dial having corresponding central openings formed therein. The bushing with the needle attached is then positioned against the outer face of the bottom of the inner casing, as shown in Fig. 2, and upset at *d'* to form a flange extending over the dial and the inner face of the bottom *b*. It will be understood of course that the dial, bearings, and bushing are all positioned within the inner casing before the latter is secured in the outer casing.

F designates the needle which is mounted on a suitable needle support *f* provided with a jewel *f'* for engagement with the bearing *d*. When the device is not in use, it is desirable to lift the needle support away from the bearing, and to this end I employ a lever *g* having one end provided with an opening which receives the bearing *d*, said inner end being adapted to engage the base of the needle support *f* in the manner shown in Fig. 2. The opposite end of the lever *g* extends through an opening *g'* in the inner casing, and is provided with an angular extremity bent upon itself, as indicated at *g''* and arranged to be engaged by suitable operating means carried by the head of the casing, and will now be described.

The head is designated at *H*, being suitably attached within an opening formed in the outer casing, and is interiorly threaded to receive the threaded portion *h* of the stem *h'*. The inner end of the stem *h'* is arranged to contact with the end *g''* of the lever *g*, and when the stem is moved inwardly by turning the knurled portion *h''*, it operates the lever *g*, moving its innermost end upwardly, and raising the needle support from its bearing, as shown in Fig. 3. The reverse movement of the stem returns the parts to the position shown in Fig. 2. It is desirable to limit the movement of the stem *h'* in either direction, and in order to accomplish this in a convenient and simple manner I provide a reduced portion *h''* on the stem and arrange a pin or plug *h''* removably in a recess in the head so as to engage the reduced portion of the stem, as

shown clearly in Fig. 4. The pin *h''* is held in position by any suitable means and in a preferred embodiment, I accomplish this by the usual swivel or spring ring designated at *h''*, which is adapted to be snapped into position in recesses in the head, and engages against the pin *h''*, securely locking it against removal.

With the structure described, I provide an arrangement that is extremely simple to manufacture and involves no expensive operations in the production of the parts. Furthermore the parts of the instrument can be separately manufactured, and assembled into the finished article without much difficulty.

I claim as my invention:

1. The combination with the bottom of a casing, of a bushing extending over the inner and outer faces of the bottom, and a bearing held frictionally within the bushing.

2. The combination with the bottom of a casing, of a dial arranged on the inner face of the bottom, a bushing engaging the outer face of the bottom and the inner face of the dial, and a bearing held frictionally within the bushing.

3. The combination with an inner casing having a bearing mounted therein, of a needle support mounted on the bearing, a lever having one end engaging said needle support and its opposite end projecting through the inner casing, an outer casing, and means carried by the outer casing having engagement with the lever to operate the same.

4. The combination with a casing, of a head having recesses therein, a stem projecting through the head and movable therein, the stem having a reduced portion, a pin projecting through the head into said reduced portion and limiting the movement of the stem, and a spring ring coöperating with said recesses in the head and engaging said pin to hold it in place.

5. The combination with a casing, of a head, a stem projecting through the head and movable therein, the stem having a reduced portion, a spring ring coöperating with recesses in the head, and means held in place by the ring and engaging said reduced portion to limit the movement of the stem.

JAMES A. HOWE.
